PERFUME ATOMIZER

Ernest P. Smith, New York, N. Y., assignor to
Premier Crystal Laboratories, Incorporated,
New York, N. Y.

Application August 12, 1946, Serial No. 639,911

6 Claims. (Cl. 299—88)

1

This invention relates to perfume dispensers, and more particularly to an improved perfume dispenser of the atomizer type adapted to be carried in a handbag, vanity case or pocket.

A main object of the invention is to provide a novel and improved perfume atomizer which is very simple in construction, easy to use, compact in size, and which may be readily carried in a pocket, handbag, vanity case, and the like, without leakage or evaporation of the perfume from the atomizer.

A further object of the invention is to provide an improved perfume atomizer comprising a small number of simple parts which are inexpensive to manufacture and easy to assemble.

Further objects and advantages of the invention will become apparent from the following description and claims, and from the accompanying drawings, wherein:

Figure 1 is an elevational view of a perfume atomizer constructed in accordance with the present invention, the atomizer being shown in closed position.

Figure 2 is a vertical cross-sectional view taken on line 2—2 of Figure 1.

Figure 3 is an elevational view, partly in cross-section, of the atomizer of Figure 1, shown in extended, or released, position.

Figure 4 is an enlarged detail view in horizontal cross-section, taken on line 4—4 of Figure 2.

Figure 5 is an enlarged horizontal cross-sectional view taken on line 5—5 of Figure 3.

Figure 6 is a detail cross-sectional view taken on line 6—6 of Figure 5.

Figure 7 is an elevational detail view of the perfume reservoir member employed in the atomizer of Figure 1.

Figure 8 is an elevational detail view of a diffuser element employed within the perfume reservoir.

Figure 9 is an elevational detail view of a plunger member employed in the atomizer of Figure 1.

Figure 10 is an elevational detail view of a bottom cap member employed in the atomizer of Figure 1.

Figure 11 is an elevational detail view, partly in cross-section, of a hollow plunger screw employed in the atomizer of Figure 1.

Referring to the drawings, 11 designates a cylindrical barrel member. Threadedly secured to the bottom end portion of barrel member 11 is a bottom cap member 12, said bottom cap being formed with an axial bore 43. Slidably mounted within barrel member 11 is a plunger member 13.

Secured to plunger member 13 by a screw member 14 and a bearing washer 15 is a deformable sealing washer 16 of rubber, leather, or other suitable yielding material, which is in slidable but sealing engagement with the inside wall surface of barrel member 11. A coil spring 17 bears between washer 15 and an annular seat 18 formed therefor in bottom cap member 12 to bias plunger member 13 upwardly with respect to the bottom cap member. Screw member 14 is formed with an axial bore 19 for a purpose presently to be described.

Plunger member 13 is reduced in outer diameter with respect to its lower end portion to define an annular shoulder 20. Shoulder 20 cooperates with an annular rib 21 formed inside barrel 11 adjacent its top end to limit extension of plunger member 13 upwardly with respect to barrel 11 resulting from the free expansion of spring 17, as shown in Figure 3.

Plunger member 13 is formed with an internal cavity having a conical bottom surface 22. Secured within this cavity by press-fitting or other suitable rigid securing means is a reservoir member 23 having an externally threaded upper end portion 24. The bottom surface 25 of the reservoir member is flat except for a substantial bevel 26. The side surface of said reservoir is cylindrical and reduced in diameter with respect to the adjacent inner surface of plunger member 13 to define an air passage 27. It will be noted that the bevel 26 is so oriented with respect to conical surface 22 as to provide an annular restricted passage similar in effect to a Venturi orifice between the center portion of surface 22 and the peripheral portion thereof.

Secured in the upper portion of the wall of plunger member 13 is a nozzle element 28, shown in elevational view in Figure 2 and in cross-sectional view in Figures 4 and 5. Aligned with the orifice in nozzle element 28 is an orifice 29 formed in the wall of reservoir member 23. A recess 30 formed in the upper shouldered portion of reservoir member 23 provides communication between air space 27 and the space intervening between orifice 29 and nozzle element 28.

Positioned inside reservoir 23 and in engagement with its inner wall surface is a diffuser sleeve 31. Said diffuser sleeve is formed with a diamond-knurled exterior surface 32 to retard the passage of perfume liquid from the reservoir upwardly along the inner wall surface of the reservoir to orifice 29. The bottom of the reservoir is conical, as shown at 33, and a pair of semi-circular notches 34 are formed in the bottom edge

of sleeve 31 to allow the fluid to flow freely under said bottom edge. The lower end portion of the outer surface of sleeve 31 is slightly reduced in diameter, as shown at 35 in Figure 8 to further promote flow of the perfume fluid to the diffusing surface of the sleeve. Said diffusing surface is normally covered with a film of perfume liquid, and the atomizing action consists in drawing perfume liquid from this film out through nozzle 28 in the form of a fine spray or mist. When the atomizer is not in use, the flow-retarding action of the roughened outer surface of the sleeve 31 prevents leakage of the fluid from the atomizer.

Threadedly engaged with threaded portion 24 of reservoir member 23 is a top closure cap 36. A sealing gasket 37 is interposed between closure cap 36 and the rim of reservoir 23.

The top rim portion of barrel member 11 is formed with a flange having an annular inwardly directed rib 38. Rib 38 defines with annular rib 21 an annular groove 39. Nozzle member 28 is provided with an outer head portion or flange 40, shown most clearly in Figure 5, which is received in groove 39 to lock plunger member 13 in retracted position in barrel 11 when the atomizer is not in use. A rectangular notch 41 is formed in rib 38 to permit head portion 40 to be disengaged from groove 39 when the atomizer is to be used to spray perfume.

When the atomizer is not in use the parts are in the position shown in Figures 1 and 2, with plunger member 13 retracted in barrel 11 against the pressure of spring 17 and locked by the engagement of nozzle head 40 in groove 39. To use the atomizer, cap 36 is grasped and is rotated with respect to the barrel 11 until nozzle head 40 registers with rectangular notch 41, permitting the plunger member 13 to be extended by the expansion of spring 17. The operator then places his thumb over the bottom opening of bore 43 in the bottom cap 12 and presses downwardly on top cap 36. The air trapped in the lower portion of barrel 11 is compressed and passes through bore 19 of the plunger screw 14 into the central space below the flat bottom surface 25 of the reservoir. The compressed air then passes radially through the annular Venturi-like restriction defined between the lower circular edge of the reservoir bottom surface 25 and the conical surface 22 with a subsequent throttling action and is greatly accelerated. The air leaving the Venturi portion passes through the air space 27 and out through nozzle 28. Since the rapidly moving air in the space between nozzle 28 and orifice 29 provides a low pressure or suction effect, liquid is drawn from the diamond-knurled surface of sleeve 31 through the orifice 29 and is combined with the low pressure air stream to produce a fine spray or mist emerging from nozzle 28, consisting of a mixture of air and particles of perfume fluid.

The use of the annular Venturi structure defined by bevel 26 and conical surface 22 effects such a substantial building up of air velocity at nozzle 28 that the diamond knurled sleeve 31 may be relatively close-fitting with respect to the inside surface of the reservoir 31 without causing a break in the continuity of the liquid film on the diamond knurled surface during the atomizing action. By the use of a close-fitting sleeve in the reservoir, leakage of the liquid from the atomizer when it is not in use is substantially eliminated. The atomizer may thus be carried in any position in a pocket or handbag without

danger of leaking, and the contents of the reservoir will not evaporate therefrom even when the atomizer is not used for long periods of time.

On the release stroke, the operator uncovers the bottom opening of bore 43 and allow spring 17 to expand, causing plunger 13 to move to its extended position. During this process air enters reservoir 23 through orifice 29 and flows into the upper portion of the reservoir past the upper portion of knurled sleeve 31 to restore the pressure in the upper portion of the reservoir to atmospheric.

While a specific embodiment of a perfume atomizer has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. An atomizer comprising a barrel member, a hollow plunger slidably contained within and sealingly engaging the inner wall surface of said barrel member, a reservoir for liquid material rigidly carried within said plunger and movable therewith, said reservoir being reduced in outer diameter below its top portion, defining a substantially enclosed air space between its outer wall surface and the inner wall surface of said plunger, means defining an annular restriction between the bottom of the reservoir and the bottom wall of the plunger, a nozzle orifice formed in the wall of the plunger and communicating with said air space, an orifice formed in the reservoir wall in alignment with said nozzle orifice, and a sleeve member closely fitting inside the reservoir and overlying the reservoir orifice, the outer surface of the sleeve member being roughened to define capillary passages between the sleeve member and the inner wall surface of the reservoir, said plunger being formed with an air admission orifice in its end portion communicating with said air space.

2. An atomizer comprising a barrel member, a hollow plunger slidably contained within and sealingly engaging the inner wall surface of said barrel member, spring means biasing said plunger to an extended position with respect to said barrel member, a reservoir for liquid material rigidly carried within said plunger and movable therewith, said reservoir being reduced in diameter below its top portion, defining an air space between its outer wall surface and the inner wall surface of said plunger, means defining an annular restriction between the bottom of the reservoir and the bottom wall of the plunger, a nozzle orifice formed in the wall of the plunger and communicating with said air space, an orifice formed in the reservoir wall in alignment with said nozzle orifice, a sleeve member closely fitting inside the reservoir and overlying the reservoir orifice, the outer surface of the sleeve member being roughened to define capillary passages between the sleeve member and the inner wall surface of the reservoir, said plunger being formed with an air admission orifice in its end portion communicating with said air space, and an end cap carried by said barrel member, said end cap having an air admission orifice formed therein.

3. An atomizer comprising a barrel member, a hollow plunger slidably contained within and sealingly engaging the inner wall surface of said barrel member, spring means biasing said plunger to an extended position with respect to said

barrel member, cooperating stop means carried by said plunger and barrel member limiting the extension of the plunger, a reservoir for liquid material rigidly carried within the plunger and movable therewith, said reservoir being reduced in outer diameter below its top portion, defining an air space between its outer wall surface and the inner wall surface of said plunger, means defining an annular restriction between the bottom of the reservoir and the bottom wall of the plunger, a nozzle orifice formed in the wall of the plunger and communicating with said air space, an orifice formed in the reservoir wall in alignment with said nozzle orifice, a sleeve member closely fitting inside the reservoir and overlying the reservoir orifice, the outer surface of the sleeve member being roughened to define capillary passages between the sleeve member and the inner wall surface of the reservoir, said plunger being formed with an air admission orifice in its end portion communicating with said air space, and an end cap carried by said barrel member, said end cap having an air admission orifice formed therein.

4. An atomizer comprising a barrel member, a hollow plunger slidably contained within and sealingly engaging the inner wall surface of said barrel member, spring means biasing said plunger to an extended position with respect to said barrel member, cooperating stop means carried by said plunger and barrel member limiting the extension of said plunger, a reservoir for liquid material rigidly carried within said plunger and movable therewith, said reservoir being reduced in outer diameter below its top portion, defining an air space between its outer wall surface and the inner wall surface of said plunger, means defining an annular restriction between the bottom of the reservoir and the bottom wall of the plunger, a nozzle member carried in the side wall of the plunger and communicating with said air space, means carried by the barrel member cooperating at times with said nozzle member to lock the plunger in retracted position within the barrel member, an orifice formed in the reservoir wall in alignment with said nozzle member, a sleeve member closely fitting inside the reservoir and overlying said orifice, the outer surface of said sleeve member being roughened to define capillary passages between the sleeve member and the inner wall surface of the reservoir, said plunger being formed with an air admission orifice in its end portion communicating with said air space, and an end cap carried by said barrel member, said end cap having an air admission orifice formed therein.

5. An atomizer comprising a barrel member, a hollow plunger slidably contained within and sealingly engaging the inner wall surface of said barrel member, an end cap carried by said barrel member, said end cap having an air opening formed therein, a coil spring bearing between said end cap and said plunger, whereby said plunger is biased toward an extended position with re-

spect to said barrel member, cooperating stop means carried by said plunger and barrel member limiting the extension of the plunger, a reservoir for liquid material rigidly carried within said plunger and movable therewith, said reservoir being reduced in outer diameter between its top portion and its bottom to define an air space between its outer wall surface and the inner wall surface of the plunger, the bottom periphery of the reservoir being bevelled and the inner bottom surface of the plunger being conically formed adjacent the bottom periphery of the reservoir to define an annular restriction with respect to the bottom edge of the reservoir, nozzle means in the side wall of the plunger communicating with the upper portion of said air space, the reservoir wall being formed with an orifice aligned with said nozzle means, and a sleeve member closely fitting inside the reservoir and overlying said orifice, the outer surface of the sleeve member being roughened to define capillary passages between the sleeve member and the inner wall surface of the reservoir, said plunger having an air admission orifice formed in its end wall communicating with the portion of said air space below said annular restriction.

6. An atomizer comprising a barrel member, a hollow plunger slidably contained within and sealingly engaging the inner wall surface of said barrel member, a reservoir for liquid material rigidly carried within said plunger and movable therewith, said reservoir being bevelled at its bottom periphery and the inner bottom surface of the plunger being conically formed adjacent the bottom edge of the reservoir to define an annular restriction, the reservoir being reduced in outer diameter above said annular restriction to define an air space, nozzle means in the side wall of the plunger communicating with said air space, the reservoir wall being formed with an orifice in alignment with said nozzle means, the end wall of the plunger being formed with an air admission orifice communicating with the space below said annular restriction, and a sleeve member closely fitting inside the reservoir and overlying the orifice in the reservoir wall, the outer surface of the sleeve member being roughened to define capillary passages between the sleeve member and the inner wall surface of the reservoir.
